SUCTION CLEANER BRUSH

Eugene F. Martinet, Cleveland, Ohio, assignor to
 The P. A. Geier Company, Cleveland, Ohio, a
 corporation of Ohio

Application October 6, 1933, Serial No. 692,482

3 Claims. (Cl. 15—8)

The invention relates to brushes for suction cleaners, and more particularly to a rotary brush adapted to be journaled in the suction nozzle of the cleaner, and this application is a continuation in part of the common subject matter of my prior application, Serial No. 623,804, filed July 21, 1932, entitled Suction cleaning apparatus.

For general purposes, it is desirable to provide a suction cleaner having a rotary, preferably motor driven brush mounted in its suction nozzle for quick and easy detachment therefrom.

It is likewise desirable to have the brush adjustable with respect to the nozzle, so that the position of the brush may be adjusted relative to the surface being cleaned to compensate for bristle wear and/or surface characteristics.

It is therefore an object of the present invention to provide a detachably and adjustably mounted rotary brush in a suction cleaner nozzle, arranged so that the position of the brush with respect to the nozzle and the surface being cleaned may be adjusted to compensate for bristle wear and/or surface characteristics.

In certain prior suction cleaner constructions embodying a rotary brush in the suction nozzle, the fine dust or dirt particles passing through the nozzle have had access to the bearings of the brush, with the result that these particles may collect and build up in the bearings to the extent of clogging and slowing down or even stopping the rotation of the brush.

Where the brush is driven by the motor of the cleaner, this clogged condition of the brush bearings increases the load on the motor and consequently reduces the efficiency of the cleaner.

This difficulty has been overcome by the construction disclosed herein and in my prior application, Serial No. 623,804, in which hub caps are journaled on brush axle pins, and in which the hub caps are provided with inwardly extending annular flanges that surround and enclose cylindrical bosses on the ends of the brush. Such a construction effectively seals the bearings for the hub caps on the axle pins against the collection of dust and dirt.

However, I have found that hair, long threads, string and the like, which are picked up by the cleaner or by the brush thereof, wind around the brush and the ends thereof and collect about the hub caps and between the sealing or shielding flanges thereof and the brush bosses; with the result that rotation of the brush is retarded and in some cases even stopped, thus reducing the efficiency of the cleaner.

Accordingly, it is a further object of the pres-

ent invention to provide a brush construction in which the collection of dust particles in and around the brush bearings is substantially eliminated; and in which the collection of threads, string, hair and the like around the brush hub caps is eliminated.

And finally, it is an object of the present invention to provide a suction cleaner brush incorporating the foregoing objectives in a simple, compact and inexpensive construction, which is quickly and easily adjusted or replaced.

These and other objects are accomplished by the improvements comprising the present invention, which may be stated in general terms as including in a detachable suction cleaner brush construction, an eccentric bearing mounting for the brush including a hub cap, means for shielding the brush bearings from dust and dirt, and means for shielding the hub caps from the collection of threads, string, hair and the like.

Referring to the drawing forming part hereof

Figure 1 is a fragmentary side elevation of a suction cleaner embodying the present improvements, part of the nozzle being shown in section, as on line 1—1, Fig. 2;

Fig. 2 is a section through the brush nozzle, taken substantially on line 2—2, Fig. 1;

Fig. 3 is an enlarged fragmentary sectional view similar to Fig. 2, showing one of the brush mountings and the shielding and sealing means therefor; and

Fig. 4 is a transverse section thereof, taken on line 4—4, Fig. 3.

Similar numerals refer to similar parts throughout the several views.

A usual type of suction cleaner is shown in Fig. 1, comprising a motor in a motor housing 10, and a fan in the fan housing 11 mounted on the motor shaft. An operating handle is connected to the handle bracket 12, and a dust bag (not shown) is connected to the exhaust side of the fan housing 11. The motor housing 10 and the fan housing 11 are mounted on front casters 13 and an adjustable rear caster 14.

The brush nozzle includes walls forming a tubular neck 15, and an elongated brush housing suction mouth 16. The improved rotary brush is indicated generally at 17, is provided with bristles 18, and is detachably and adjustably rotatably mounted in the suction mouth 16.

The brush 17 is preferably motor driven, as shown in the drawing, and is provided with a crown pulley rib 19, around which an endless preferably rubber belt 20 passes; and the belt 20 passes around a shaft 21 preferably detachably con-

nected to the motor shaft, for driving the brush. The rotary brush 17 is preferably removably and adjustably mounted in the brush housing nozzle mouth 16 by means of an end bearing construction shown in Figs. 2, 3 and 4.

The brush member 17 includes a shaft 17a preferably of wood having enlarged end shanks 22 each provided with an annular end-opening groove 23 forming the inner cylindrical boss portion 24 and the outer annular flange 25, preferably projecting longitudinally outward slightly beyond the cylindrical boss portion 24.

A cup-shaped ferrule member 26 is tightly fitted over each cylindrical boss portion 24 for preventing the ends of the wooden shaft 17a from splitting, and an axial hole 27 is then provided in each end of the shaft 17a through the ferrule 26 into which an axle pin 28 is driven to make a tight fit.

20 A bearing block 29, preferably octagonally shaped in cross section as shown in Fig. 4, is journaled on each pin 28 by the bore 30, which is preferably eccentrically located through each block, the blocks being retained on the pins 28 abutting the adjacent ferrules 26 by split rings 31 mounted on the outer end of each pin.

An annular hub cap 32 having a preferably squared tubular shank 33 is mounted on and encloses each block 29 so as to enclose the outer end 30 of axle pins 28, and the squared shank 33 of each hub cap is preferably eccentrically located on the hub cap 32 to correspond with the eccentric location of the bore 30 through the block 29.

The annular flange portion 34 of each hub cap extends well into the adjacent annular groove 23 in the brush shaft 17a, so that the open end of the hub cap is shielded by the annular flange 25.

A integral brush mounting clip 35, preferably 40 U-shaped in cross section with spring retaining fingers 36, is rigidly mounted by rivets 37 on each inner end of the brush housing nozzle mouth 16, and each U-shaped spring fingered clip 35 forms substantially three sides of a square with 45 a restricted entrance opening between the fingers 36 as shown in Fig. 4, for receiving the squared shanks 33 of the hub caps 32 mounted on the axle pins 28.

When the brush is mounted in the brush housing nozzle mouth, the blocks 29 are maintained stationary with respect to the nozzle walls by means of the clips 35, while the axle pins 28 are stationary with respect to the brush shaft 17a and rotate in the bearing blocks 29 when the brush is rotated, as by the drive belt 20.

By detaching shaft 21 and removing it from the brush housing nozzle 16, the belt 20 is released and the brush 17 may be readily removed from the nozzle for any desired purpose. Likewise, by reason of the eccentricity of the outer squared surface of the hub cap shanks 33 with respect to the axle pins 28, the hub cap shanks 33 may be inserted into the U-shaped brush mounting clips 35 in any one of each of four positions, which will locate the axis of the brush at different levels with respect to the plane of mouth of the brush housing nozzle; and in this manner the brush may be adjusted to compen-

sate for bristle wear or particular characteristics of the surface being cleaned.

Moreover, the bearings of the brush are shielded or sealed against the collection of dust and dirt by the inwardly extending annular flanges 34 5 of the hub caps 32, which surround the ferrule reinforced bosses 24 of the brush.

Likewise, the hub caps are shielded or sealed against the collection of hair, long threads, string and the like, at the inner ends of the flanges 34 10 thereof, and between the flanges 34 and ferrule members 26 by the outwardly extending annular flanges 25 of the enlarged end shanks 22 of the brush.

Also the flanges 25 increase the sealing effect for the brush bearings against the collection of dust and dirt particles in and around the same.

It has been found in actual practice that in a suction cleaner embodying the present improved 20 shielding and sealing means, the collection of dust and dirt particles in and around the brush bearings is eliminated, and the collection of string, threads, hair and the like around the brush hub caps is also eliminated, so that a high operating 25 efficiency of the cleaner is continuously maintained.

The present improved suction cleaner brush is simple, compact and inexpensive in construction, and may be quickly and easily adjusted or 30 replaced by inexperienced or unskilled persons.

I claim:

1. In a suction cleaner including a nozzle, a rotatable brush within the nozzle provided with a cup-shaped reinforcing ferrule at each end, 35 an axle pin in each end of the brush extending through the adjacent ferrule, a block eccentrically journaled on each pin abutting the adjacent ferrule, a squared hub cap mounted on each block, and integral U-shaped spring clips in the nozzle 40 detachably mounting the hub caps therein.

2. In a suction cleaner including a nozzle, a rotatable brush within the nozzle, the brush including a shaft, each end of the shaft being provided with an outwardly opening annular groove, 45 a hub cap rotatably journaled on each end of the shaft, each hub cap having a squared shank eccentric to the shaft and an annular flange extending into said annular groove, and an integral U-shaped spring clip rigidly mounted on each 50 end of the nozzle, each clip having a squared portion selectively and detachably mounting a hub cap shank in the nozzle in a plurality of different positions.

3. In a suction cleaner including a nozzle, a 55 rotatable brush within the nozzle, the brush including a shaft, each end of the shaft being provided with an outwardly opening annular groove, a hub cap rotatably journaled on each end of the shaft, each hub cap having a squared shank 60 eccentric to the shaft and an annular flange extending into said annular groove, and an integral U-shaped spring clip rigidly mounted on each end of the nozzle, each clip having a squared portion with a restricted entrance opening selectively 65 and detachably mounting a hub cap shank in the nozzle in a plurality of different positions.

EUGENE F. MARTINET.
